STRETCHING MACHINE GRIP

Frank T. Cope, Salem, Ohio, assignor to The
Electric Furnace Company, Salem, Ohio, a cor-
poration of Ohio

Application September 19, 1932, Serial No. 633,800

9 Claims. (Cl. 153—35)

This invention relates to stretching machine grips and is herein particularly illustrated and described as applied to grips for use in the straightening of sucker rods.

5 In the copending application of Arthur H. Vaughan, Serial No. 633,799, filed September 19, 1932, there is illustrated and described a machine for stretching sucker rods and thereby straightening them. The present invention, while use-
10 ful in a machine made according to the Vaughan invention, is also susceptible of other uses, and only so much of the said machine as is necessary for the understanding of the present invention will be described here.

15 Sucker rods such as are used in deep wells comprise a body which may be upwards of 30 ft. long and end portions so arranged that the rods may be screwed together. Usually one end of the rod, termed the "pin" end, is provided with
20 a tapered male thread and the other end, termed the "box" end, is provided with a corresponding female thread. A squared portion is also provided to accommodate a wrench and the squared or wrench portion is usually connected to the body
25 by an intermediate tapered portion. It is desirous to heat treat the sucker rods to improve their physical characteristics and the heat treatment generally results in the rods getting crooked. The machine described in the Vaughan
30 application above referred to is for the purpose of stretching the rods while still hot and thus removing any crookedness resulting from the heat treatment. In stretching the rods, it is important that the end portion be accurately alined with
35 the body portion.

It has been heretofore proposed to engage the sucker rods by the squared wrench portions for the purpose of stretching them. This has not proved satisfactory for two reasons;—difficulty is encountered in alining the end portions of the rod with the body; and the wrench squares on the two ends are frequently not oriented alike, due to the fact that the two ends are separately forged, and consequently it is difficult to arrange the gripping dies in the machine so as to properly grip both ends of the rod.

40 I overcome these objections and insure accurate alinement of the several portions of the sucker rod by dispensing entirely with engagement of the squared wrench portion and instead engaging the body, the head and the tapered intermediate portion. The grips may be used for either the pin end or the box end of the rod and they accommo-
45 50 55 date themselves to any inaccuracies or variations

within the tolerances such as ordinarily expected in a drop-forging operation.

In the accompanying drawing, illustrating a present preferred form of the invention,

Figure 1 is a horizontal section illustrating a 60 pair of the improved grips together with a portion of the stretching machine, and

Figure 2 is a like view showing the other pair of 65 grips for simultaneously engaging the other end of the rod.

The sucker rod illustrated in Figures 1 and 2 comprises a body in the form of a long cylindrical rod R, a pin end P and a box end B. Square wrench portions W are provided just back of the two ends of the rod and these wrench portions are connected to the rod-like body R by tapered intermediate portions T. 70

Figure 1 shows the grips for engaging the box end of the rod. A jaw 2 is fixed in a member 3 of the stretching machine. A companion jaw 4 75 is dove-tailed to a slide 5 movable through a toggle mechanism 6 so as to bring the die 4 into and out of gripping relation with the fixed die 2. The line of separation of the two jaws is indicated at 7. I have shown a double line for clarity of 80 illustration, but in practice the jaws will be moved into contact with one another.

The recesses in the jaws 2 and 4 are identical since the line of separation is on the axis of the sucker rod. Each of the jaws is provided with 85 a semicircular recess 8 to accommodate the body R of the sucker rod. The recess 8 is only slightly larger in diameter than the body of the rod. It thus receives the body and alines it with the axis of the die opening. A slight clearance is 90 provided, as shown in the drawing. This takes care of variations, within tolerances, in the diameters of individual rods. The recess 8 is flared out as indicated at 9, thereby forming a shoulder which engages the intermediate tapered or 95 shoulder portion T of the sucker rod and limits endwise movement of the rod. The maximum diameter of the recess is indicated at 10. It is very slightly larger than the diameter of the box end B of the rod. It thus clears and does 100 not engage in any way the squared wrench portion W. It does engage and aline the box end B with the body R.

The grips illustrated in Figure 2 are identical with those illustrated in Figure 1 and they are 105 mounted in a like machine member 3a. Portions of the apparatus illustrated in Figure 2 have been given the same reference characters as in Figure 1 with an "a" suffixed thereto. The jaws shown in Figure 2 are illustrated as engag- 110

ing the pin end of the rod. The pin end has a portion P^1 which is of the same external diameter as the box end. Figure 2 also illustrates a forging flash F which has been formed in making the pin end and which has not as yet been trimmed off. The jaws $2a$ and $4a$ may be recessed as indicated at 11 to accommodate this flash.

As shown in the drawing, the two sets of grips 10 are aligned with one another when in use. In using the grips, the toggle members 6 and $6a$ are actuated so as to separate the jaws and a hot rod to be straightened is dropped in place. The toggle members are then actuated to bring 15 the jaws together, as shown in the drawing. In this position there is, as stated, a certain amount of clearance between the grip faces and the sucker rod body and end portions. One of the frame members, in this case the member $3a$, is moved 20 in the direction of the arrow A so as to stretch the rod. This movement first takes up any clearance between the tapered portions T of the sucker rod and the corresponding tapered faces 9 and $9a$ of the gripping jaws. Such faces prevent 25 further endwise movement of the rod relative to the dies and subsequent movement of the member $3a$ away from the member 3 results in stretching the rod. After the stretching operation, the tension is released, the grips are opened 30 and the member $3a$ is moved back toward the member 3.

My improved grips engage the rod so as to stretch the same, but without leaving any undesirable marks thereon. At the same time they 35 properly align the end portions of the sucker rod with the body. Since all of the portions which the grips engage are cylindrical in cross section, it makes no difference whether the wrench squares are properly oriented with respect to one another or not, as the grips will 40 work equally well in any case. The grips accommodate themselves to the variations in size usually encountered in forging operations. They are subject to relatively little wear and the tapered portions 9 may be redressed should occasion 45 require without enlarging the diameters of the portions 8 and 10 and thereby affecting the fit of the jaws. Until the tapered portions of the sucker rod come into engagement with the 50 tapered portions of the grip, the sucker rod may slide freely through the grip. Consequently, the original length of the rods may vary considerably and still be quickly inserted in the machine and without manipulation thereof to initially 55 space the grips in an amount corresponding to the length of the rod. These variations are all taken up in the first movement of the grips away from one another prior to bringing the tapered portions of the rod into engagement with the 60 corresponding portion of the grip.

I have illustrated and described a present preferred embodiment of the invention. It will be understood, however, that this is by way of illustration only and that it may be otherwise embodied within the scope of the following claims.

I claim:

1. A grip for an object having a body, an enlarged end and an intermediate shouldered portion, comprising a gripping jaw having a recess 70 of a size adapted to receive and aline the body in the die, an adjacent shoulder adapted to engage the intermediate shouldered portion of the object and limit endwise movement thereof, and a recess lying beyond the shoulder and adapted 75 to engage the head and aline it with the body.

2. A grip for an object having a body, an adjacent shouldered portion, a wrench engaging portion of smaller size and an enlarged head, comprising a jaw having therein a recess of a size adapted to receive and aline the body in the die, the recess enlarging to accommodate the shouldered portion and engage the same in such manner as to limit endwise movement of the object and then continuing in enlarged size to receive and aline the head with the body while leaving the wrench receiving portion unengaged. 80

3. Gripping dies for an object having a body, shouldered portions at each end, wrench engaging portions of smaller size adjacent the shouldered portions, and enlarged heads at the ends of the body, comprising jaws associated with each end of the object and having therein recesses of a size adapted to receive and aline the body in the dies, the recesses enlarging to accommodate the shouldered portions and engage the same so as to limit endwise movement of the object and then continuing in enlarged size to receive and aline the heads with the body while leaving the wrench receiving portions unengaged. 85

4. A gripping die for an object having a body, 100 an enlarged end and an intermediate tapered portion, comprising a gripping jaw having a recess of a size adapted to receive and aline the body in the die, the recess flaring to accommodate the tapered portion and engage the same 105 so as to limit endwise movement of the object, and a recess lying beyond the flared portion and adapted to engage the head and aline it with the body.

5. A gripping die for an object having a body, 110 a head and an intermediate shouldered portion, comprising a gripping jaw having a recess of a size adapted to receive and aline the body in the die, an adjacent shoulder adapted to engage the intermediate shouldered portion of the 115 object and limit endwise movement thereof, and a recess lying beyond the shoulder and adapted to engage the head and aline it with the body. 120

6. A gripping die for an object having a body, a head and an intermediate shouldered portion, 125 comprising a gripping jaw having a recess of a size adapted to receive and aline the body in the die, an adjacent shoulder adapted to engage the intermediate shouldered portion of the object and limit endwise movement thereof, a recess lying beyond the shoulder and adapted to engage the head and aline it with the body, the first mentioned recess being slightly larger than the body so as to snugly surround the same yet to permit of accommodating rods varying slightly 130 from one another in diameter. 125

7. A gripping die for an object having a body, a head and an intermediate shouldered portion, comprising a gripping jaw having a recess of a size adapted to receive and aline the body in the die, an adjacent shoulder adapted to engage the intermediate shouldered portion of the object and limit endwise movement thereof, a recess lying beyond the shoulder and adapted to engage the head and aline it with the body, the last mentioned recess being slightly larger than the head so as to snugly surround the same yet to permit of accommodating rods whose heads vary slightly in size from one another. 135

8. A gripping die for an object having a body, 140 a head and an intermediate shouldered portion, comprising a gripping jaw having a recess of a size adapted to receive and aline the body in the die, an adjacent shoulder adapted to engage the intermediate shouldered portion of the 145 object and limit endwise movement thereof, and a recess lying beyond the shoulder and adapted to engage the head and aline it with the body. 150

object and limit endwise movement thereof, a recess lying beyond the shoulder and adapted to engage the head and aline it with the body, the first mentioned recess being slightly larger than the body so as to snugly surround the same yet to permit of accommodating rods varying slightly from one another in diameter, and the other recess being slightly larger than the head so as to snugly surround the same yet to permit of accommodating rods whose heads vary slightly in size from one another.

9. A grip for an object having a body, an enlarged end and an intermediate shouldered portion, comprising a fixed and a movable gripping jaw providing a recess of a size adapted to receive and aline the body in the die, an adjacent shoulder adapted to engage the intermediate shouldered portion of the object and limit endwise movement thereof, and a recess lying beyond the shoulder and adapted to engage the head and aline it with the body.
